UNITED STATES PATENT OFFICE.

CHARLES OWENS, OF CHATTANOOGA, TENNESSEE.

TILLING-MACHINE.

1,294,346.

Specification of Letters Patent. Patented Feb. 11, 1919.

Application filed June 5, 1918. Serial No. 238,380.

To all whom it may concern:

Be it known that I, CHARLES OWENS, a citizen of the United States, and resident of Chattanooga, Tennessee, have invented certain new and useful Improvements in Tilling-Machines, of which the following is a specification.

My invention relates to machines for tilling the soil in which rotary tilling implements turning about substantially vertical axes are arranged at the rear of the machine, and are driven from the traction wheel.

The invention consists in the features and combination and arrangements of parts hereinafter described, and pointed out in the claims.

In the accompanying drawing;

Figure 1 is a side elevation of a machine embodying my improvement.

Fig. 2 is a plan view of the traction wheels with the mechanism immediately associated therewith, the front portion of the machine being omitted.

Fig. 3 is a rear view of the machine.

Fig. 4 is an elevation of parts shown in Fig. 2, the traction wheel being removed, but indicated in dotted lines, and some of the parts being shown in section.

Fig. 5 is a plan view of a modified rotating head with the tilling blades mounted directly thereon.

In these drawings α indicates the traction wheels, each being mounted on a shaft as at α' , these shafts being in alinement and connected with differential gear mechanism inclosed in a casing α'' , this differential mechanism being substantially the same as that well known, for instance in the Ford automobile. 1 is a bevel gear connected to the hub of the traction wheel in any suitable way. 3 is a bevel pinion carried by a vertical shaft 4' mounted in a bracket 4, which has a sleeve portion 4^a adapted to turn about the shaft housing α^3 . This sleeve of bracket 4 has a long bearing on the shaft housing and near the inner ends of these sleeve portions bearings 5' are provided to receive the pivot pins of the rearwardly extending beams 5. These beams are adapted to turn in a horizontal direction, or are at right-angles to the direction in which the sleeve bracket 4 can turn about the axle housing α^3 . At the rear ends of the beams 5 are vertical sleeves or bearings 5'', in which shafts 13 are journaled, said shafts being sustained by collars 13' fixed thereto and resting on the

top of the bearing sleeves 5''. On these shafts 13 a rotary head 6 is mounted, and this head has associated therewith an upper plate 6^a connected thereto by vertical bearing pins 6^b on which are journaled supports 7 carrying the tilling blades 8, these tilling blades being arranged in groups on each one of the supports 7. The supports 7 can turn on the journal pins 6^b and for giving them their movement each is provided with a roller 9 to run on a stationary cam 10, which is fixed to the lower end of the sleeve or bearing 5''. The roll 9 is kept in contact with the periphery of the fixed cam by the pressure resulting from the passage of the blades 8 carried thereby through the soil. The shafts 13 are rotated by sprocket wheels 14 on their upper ends, each of which in turn is operated by a sprocket chain 14' driven from a sprocket 14'' which is connected with a sprocket wheel 12 on a stud 12', extending up from the inner end of the bracket 4. The sprocket 12 is driven from a sprocket wheel 11 on the shaft 4'. 80

It will be noticed that the axes of the sprockets 12 and 14' are coincident with the pivot pins of the beams 5, so that these beams can swing laterally on their pivots, while maintaining the driving connection to the vertical shafts 13 from the said sprockets 12 and 14', and further the beams 5 can have movement in a vertical plane by the turning of the sleeve bracket 4 about the axle housing without disturbing the driving connection from the sprocket wheels 11 to the rotating heads, because these sprocket wheels 11, together with the pinions 3 and the sprockets 12 are all mounted on the sleeve bracket 4 and thus in all positions that the beams 5 may assume in a vertical plane the connection between the pinion 3 and the gear wheel 1 will be maintained. Thus the beam 5 may have both lateral swinging movement, or adjustment, and a movement 90 in a vertical plane. 95

For adjusting the sleeve bracket 4 about the shaft housing α^3 I provide a quadrant 4^x on the sleeve bracket which is engaged by a toothed segment 14^x, which is carried by a lever 15 pivotally mounted on the frame 24. This lever may be operated, either by the hand or foot, for which latter purpose foot rests 15' are provided. The lever 15 may be held in any of its adjusted positions by a spring catch 15^a engaging openings in a segment 15^b. 105 110

Clutches are provided at 17 controlled by the hand levers 18 for disengaging the driving mechanism leading to the rotary heads. The beams 5 are provided with a slot, or opening, at α , through which extend tongue members 19. These are fixed to the frame, or are fixed to the sleeve brackets at 19', so as to turn therewith and maintain their relation to the beams 5 in a vertical direction.

10 These members are provided with arc-shaped portions 19^a which have elongated openings receiving locking pins 19^b extending down through a suitable bearing formed on the beams 5, so that the beams may be 15 set at the desired angle with the rotating cultivator or tilling heads at the desired distances apart. Some lateral play is allowed to the beams 5 within the limits of the slots. The locking pins may be withdrawn if desired, and the beams may be controlled by means of plow handles attached thereto.

At 21 I show a projection extending from the rotary sleeve bracket 4, which cooperates with an adjustable stop 22 depending 25 from the frame for regulating the depth of the tilling blades 8, the said arm 21 abutting against the lower end of the said stop to limit the downward swinging movement of the beam 5 with the rotating head 6, and 30 the blades 8. As stated the stop 22 may be adjusted vertically to change the depth to which the cutting blades may go.

These blades may be of different lengths, or rather in sets of different lengths, so that 35 by taking out one set and putting in another different depths may be cut. The blades do not rotate in or follow a path concentric with the shaft 13, but by reason of 40 mounting them upon the oscillating carriers 7 and changing the positions of these carriers at the different points around the center of the head by means of the rolls 9 working on the periphery of the stationary cam the position of the blades is constantly 45 changing in relation to the soil being cut or tilled.

The blades at the advance periphery or path of rotation always present a proper cutting surface in their relation to both the 50 forward and rotary travel of the rotating heads while on the side of the rotating heads the blades present a vertical surface to the line of travel to avoid resistance, while those blades which are at the rear 55 part of the periphery of travel present a pulverizing or crushing surface to loosen the soil, the entire action being calculated to assist the traction action of the tractor wheels.

60 When the sleeve brackets 4 are rotated by means of the segmental gears to raise the tilling heads from the soil the levers 18 are brought against stops 18' on the frame and the clutches 17 are thus thrown out of operation automatically, and the rotation of the

tilling heads is stopped. The beam 5 is free to swing laterally within the limits of the short slots in the segment. In turning the machine the operator, by lifting the rotating head, which is on the outside of the 70 path, or curve to be traversed and leaving the blades of the other head in contact with the ground, is enabled to turn the machine with greater facility than if both heads are left in use.

75 I show in Fig. 5 a modified construction of the support of the blades in which the carriers 7 and the cam 10 are eliminated, and instead each blade is pivotally mounted on a shaft loosely journaled in the rotary head 6^x. The forward edge of each blade reaches in to the center of the shaft which carries it, and each blade is independent of the other blades. As the rotating head 6^x advances with the onward movement of the 80 machine the blades naturally accommodate themselves to the position of least resistance in the soil, and they are constantly changing and are thus stirring up the soil in these 85 changing actions.

90 The engine for driving the machine is indicated at A. This is connected up to any suitable transmission mechanism which is well known in the art and which includes the differential inclosed in the casing A'' 95 before mentioned.

The driver's seat is indicated at B and the steering wheel at C. This may be connected up through the sprocket chains and suitable sprocket wheels with the ordinary 100 steering shaft D.

It will be seen from the above that the 105 tilling units or heads are arranged one on each side of the line of draft; that they are independently driven from a common differential transmission and that they are independently controlled at the will of the operator not only as to adjustment but to effect the steering of the machine by using either one or the other unit as a means for 110 placing the load or resistance on either the one side or the other of the line of draft and in rear of the traction wheel making either one or the other traction wheel the fulcrum point around which the load tends to swing 115 the machine, this effect being accomplished by raising one of the heads while leaving the other in the ground.

120 And it will be further observed that the angular relation of the blades to the soil can be changed at the will of the operator which combined with the rotary motion of the heads carrying the blades and the changing positions of the blades at different points of their travel will give different tilling or 125 pulverizing effects.

I claim:

1. In a tilling machine, traction wheels, shaft sections, one for each wheel, a differential gear transmission between said shaft 130

sections, a pair of rotary heads at the rear of the machine rotating about substantially vertical axes and means for driving said rotating heads independently, one of said means being connected to and driven from one traction wheel and the other being connected to and driven from the other traction wheel, substantially as described.

2. In a tilling machine, traction wheels, shaft sections, one for each wheel, a differential gear transmission between said shaft sections, rotary brackets turning about said shaft sections, rotary heads connected with and supported from the rotary brackets to be moved up and down by the turning of said brackets, means for turning said brackets to raise or lower the rotary heads in relation to the ground being tilled, an independent driving connection for each rotary head and blades carried by the rotary heads to work in the ground, substantially as described.

3. In a tilling machine, traction wheels, shaft sections, one for each wheel, a differential gear transmission between the shaft sections, rotary heads, blades carried thereby to work in the ground, an independent driving connection from each rotary head leading back to the shaft sections belonging thereto, and means for raising and lowering the rotary heads with their blades independently of each other, substantially as described.

4. In combination in a tilling machine, traction wheels, shafts therefor, members turnable about the shafts, beams extending rearward from said members, rotary heads mounted in the beams to turn about substantially vertical axes, means for turning the said members to raise or lower the beams with the rotary heads independently of each other and blades carried by the heads to work in the ground, substantially as described.

5. In combination in a tilling machine, traction wheels, shafts therefor, members turnable about the shafts, beams extending rearward from said members, rotary heads mounted in the beams to turn about substantially vertical axes, means for turning the said members to raise or lower the beams with the rotary heads independently of each other and blades carried by the heads to work in the ground, said beams being mounted to have lateral adjustment substantially as described.

6. In combination in a tilling machine, traction wheels, shafts therefor, members turnable about the shafts, beams extending rearward from said members, rotary heads mounted in the beams to turn about substantially vertical axes, means for turning the said members to raise or lower the beams with the rotary heads independently of each other and blades carried by the heads to work in the ground, said beams being

mounted to have lateral swinging adjustment, substantially as described.

7. In combination in a tilling machine, traction wheels, shafts therefor, members turnable about the shafts, beams extending rearward from said members, rotary heads mounted in the beams to turn about substantially vertical axes, means for turning the said members to raise or lower the beams with the rotary heads independently of each other and blades carried by the heads to work in the ground, said beams being mounted to have lateral swinging adjustment, and segmental pieces to which the beams may be connected in their different positions, substantially as described.

8. In combination in a tilling machine, rotary heads, blades to work in the ground carried thereby, a driving connection for each rotary head, a clutch for each driving connection, means for operating the clutches independently so that the rotation of each rotary head may be arrested and means for raising and lowering each rotary head independently of the other, said clutch operating means operating automatically when the corresponding head is lifted from the ground, substantially as described.

9. In a tilling machine, a rotary head, blades carried thereby to work in the ground, said blades being movably supported to turn about their vertical axes in respect to their general paths of travel whereby their angular positions may be changed at different points in said paths of travel with the head.

10. In combination in a tilling machine, a rotary head, tilling blades carried thereby to work in the ground and means for changing the position of the blades about their vertical axes and in relation to their general path of travel about the axis of the head as they revolve about the same, substantially as described.

11. In combination in a tilling machine, a rotary head, tilling blades carried thereby to work in the ground and means for changing the position of the blades about their vertical axes and in relation to their general path of travel about the axis of the head as they revolve about the same, said means including a cam fixed in relation to the rotary head.

12. In combination in a tilling machine, a rotary head, tilling blades carried thereby to work in the ground and means for changing the position of the blades in relation to their general path of travel about the axis of the head as they revolve about the same, said means including a cam fixed in relation to the rotary head and pivoted supports carried by the head and carrying the tilling blades, said supports being turned by engagement with said cam, substantially as described.

13. In combination in a tilling machine, a rotary head, tilling blades carried thereby to work in the ground and means for changing the position of the blades in relation to their general path of travel about the axis of the head as they revolve about the same, said means including a cam fixed in relation to the rotary head and pivoted supports carried by the head and carrying the tilling blades, said supports being turned by engagement with said cam, said supports being held in working engagement with the cam by the pressure from the soil, substantially as described.
14. In a tilling machine, tilling tools or blades arranged on opposite sides of the line of draft, traction wheels in rear of which the blades operate, a common driving member for the blades having a differential action, and means under the control of the operator whereby the tilling blade on one side of the line of draft is varied in its work in respect to the work performed by the blade or blades on the other side of the line of draft whereby the operator is enabled to steer the machine.
15. In combination in a tilling machine, a rotary head, tilling blades carried thereby to work in the ground and means for changing the position of the blades in relation to their general path of travel about the axis of the head as they revolve about the same, said means including a cam fixed in relation to the rotary head and pivoted supports carried by the head and carrying the tilling blades, said supports being turned by engagement with said cam, and means under the control of the operator for adjusting the blades vertically in relation to the ground being tilled, substantially as described.
16. In combination in a tilling machine, traction wheels, a shaft section for each wheel, differential transmission means between the shaft sections, tilling implements, one on each side of the line of draft, a connection from each tilling implement to the shaft section individual thereto and means under the control of the operator for varying the position of the tilling implements in relation to the ground being worked to assist in steering the machine, substantially as described.
17. In combination in a tilling machine, traction wheels, members turnable about the axis of the wheels, rotary heads having tilling blades, beams pivotally connected to said members to swing in a direction at right-angles to the plane of rotation of said members, and driving connections for said rotary heads connected to the traction wheels and extending therefrom to the pivotal axis of the beams and thence along said beams to the heads, and means for adjusting said turnable members independently to raise or lower either or both heads, said heads being on opposite sides of the line of draft, substantially as described.
18. In combination in a tilling machine, traction wheels, members turnable about the axis of the wheels, rotary heads having tilling blades, beams pivotally connected to said members to swing in a direction at right angles to the plane of rotation of said members, and driving connections for said rotary heads connected to the traction wheels and extending therefrom to the pivotal axis of the beams and thence along said beams to the heads, and means for adjusting said turnable members independently to raise or lower either or both heads, said heads being on opposite sides of the line of draft, and differential driving means for the traction wheels, substantially as described.
19. In a tilling machine, traction wheels, shaft sections, one for each wheel, a differential gear transmission between said shaft sections, a motor for driving the differential gearing, a pair of rotary tilling heads, means for driving one of said heads from one side of the differential gearing and means for driving the other head from the other side of the differential and means for raising and lowering the heads independently, substantially as described.
20. In a motor driven tilling machine, a pair of tilling implements, one on each side of the line of draft, differential transmission gearing, a connection from one side of the differential to one tilling implement to drive the same, a connection from the other side of the differential to the other tilling implement to drive the same, traction wheels and means for varying the working relation of each tilling implement in respect to the ground to aid in steering the machine.
21. In a motor driven tilling machine, a pair of tractor wheels, a pair of tilling implements, one on each side of the line of draft, differential transmission gearing, a connection from one side thereof to the traction wheel and tilling implement on one side of the line of draft, and a connection from the other side of the transmission gearing to the traction wheel and tilling implement on the other side of the line of draft and means for varying the working relation of each tilling implement in respect to the ground to aid in steering the machine, substantially as described.
